CLAIM

An ornamental design for a breakaway connector for electric fences, as shown and described.

DESCRIPTION

FIG. 1 is a perspective view of a breakaway connector for electric fences showing my new design;

FIG. 2 is a top view of the breakaway connector for electric fences shown in FIG. 1;

FIG. 3 is a right side view of the breakaway connector for electric fences shown in FIG. 1, the left side view of the breakaway connector is a mirror image of the right side view; and,

FIG. 4 is front view of the breakaway connector for electric fences shown in FIG. 1.

The uneven broken line representations of a spring loop and the nut and bolt arrangement in FIGS. 1-4 are for illustrative purposes only and form no part of the claimed design.
